Application December 17, 1947, Serial No. 792,277

10 Claims. (Cl. 62—3)

1

The present invention relates to the arts of refrigeration and air conditioning, the invention being applicable to a refrigerating system of the compressor-condenser-evaporator type whether the system be used to cool and dehumidify air for air conditioning purposes or to chill a medium surrounding the evaporator, such as air, salt brine, or a liquid such as diethylene glycol, which medium would be used for the purpose of preserving foodstuffs, producing ice, or any other purpose for which refrigerating systems are of utility.

This application is a continuation in part of my application, Serial No. 625,864, now abandoned.

The present invention is of particular application to a refrigerating system including a compressor of the type disclosed and claimed in the patent to Charles R. Neeson, No. 2,185,473, issued January 2, 1940, the present invention including a device responsive to a condition of air being conditioned or a condition of the medium surrounding the evaporator coil for effecting unloading and loading of the compressor of the refrigerating system in response to the condition.

The present invention involves a change in the construction of Gonzales Patent 2,304,999, December 14, 1942. According to that patent, a control system has a part located in the medium being cooled so as to be responsive to a given condition of the medium for acting on a valve rod for a master valve operating a variable capacity means in a compressor. The valve rod is also connected to a means responsive to suction pressure of the compressor such as a bellows. The arrangement is such that although the master valve for the variable capacity means is connected both to the condition-responsive part in the medium being cooled and to the suction-pressure-responsive means, the condition-responsive part always has complete control of the master valve, and the suction-pressure-responsive means has control only in the event that there is failure of control through the condition-responsive part.

According to the present invention, the control lies with the suction-pressure-responsive means such as the bellows, and the part responsive to a condition of the medium being cooled acts to modify the control exerted by the suction-pressure-responsive means. The result is that the suction pressure at which the compressor is unloaded is varied for a variation of the aforesaid condition in the medium being cooled.

Also according to the present invention, means responsive to an additional condition such as high suction pressure of the compressor may act to unload the compressor, and this means may be coordinated with the condition-responsive part

5 to vary the control at the same point where the condition-responsive part varies the control. The advantage in a control dependent upon high suction pressure is that it prevents overloading of the compressor motor. If, for example, the refrigerator is heavily loaded by a high temperature at the outset of the medium being cooled, this is reflected in a high suction pressure. I have discovered that the compressor should be unloaded for a reduction of load on the motor if the heavy loading is to continue for a fairly long time and that this may conveniently be done by unloading in response to a high suction pressure. The result is that the initial cooling period may be somewhat lengthened, but the compressor is not overloaded, and the size of compressor may be determined from normal maximum load after the initial cooling period rather than from the overload that often occurs in the initial cooling period.

10 The invention will be more fully understood by study of the following specification taken in connection with the accompanying drawings wherein like numerals refer to like parts throughout.

In the drawings,

15 Fig. 1 discloses an air conditioning system having the present invention applied thereto, the compressor disclosed therein being of the type covered by the aforesaid patent to Neeson.

20 Fig. 2 is a longitudinal section through a compressor having the present invention associated therewith, and showing details of the capacity varying means disclosed in the aforesaid patent to Neeson;

25 Fig. 3 is a view in elevation of the front cover of the compressor disclosed in Fig. 2, with details of the capacity regulating master valve and the operating mechanism of the present invention attached thereto;

30 Fig. 4 is an end view of the portion of the apparatus disclosed in Fig. 3;

35 Fig. 5 is a sectional view taken through the master valve mechanism and the operating mechanism;

40 Fig. 6 is a sectional view somewhat similar to Fig. 5, of a modified form of apparatus;

45 Fig. 7 is a plan view of the apparatus of Fig. 6;

50 Fig. 8 is a diagrammatic view of an electric circuit and associated means for controlling the apparatus of Figs. 6 and 7; and

55 Fig. 9 is a sectional view similar to Fig. 6 of another modified form of the apparatus.

In Fig. 1 there is disclosed an air conditioning system comprising a refrigerating system of the compressor-condenser-evaporator type of which the compressor includes a pair of unitary compressors 20 of identical construction fastened to

the opposite ends of a double-ended motor 21. The two compressors discharge into a common condenser 22 from which condensed refrigerant is expanded into an evaporator 23 having connections to the inlets of both compressors. Therefore, for all practical purposes the two compressing units may be considered as a single compressor. The evaporator 23 is located in a duct 24 through which a stream of air is drawn by a blower 25, the air passing over the evaporator being cooled and dehumidified and being then discharged into the space to be served by the action of the blower. It is, of course, readily apparent that the evaporator may be located in a food storage compartment over which air is circulated by a blower means or by gravity, or in a medium of liquid type used for various cooling purposes.

Details of one of the compressing units are disclosed in Fig. 2 wherein it is seen that the compressing unit 20 comprises a crankshaft 30 to which are connected a plurality of connecting rods 31 each operating a piston 32 in a cylinder 33. Gas which is admitted to the suction manifold 34 from the evaporator 23 passes into the interior of the cylinder through the suction valve 35 and is ejected through the discharge valve 36 into the discharge head 37 which is connected by passage 38 to the common discharge manifold 39 from which the compressed gas passes into the condenser 22. Details of the valve and piston construction may be ascertained from the aforesaid patent to Neeson, as well as the patent to Charles R. Neeson, No. 2,137,965, issued November 22, 1938.

As further explained in the aforesaid Patent No. 2,185,473, the suction manifold 34 is connected through ports 40 with the interior space 41 of the crankcase whereby a flexible, metallic bellows 42 is subjected to the pressure of the expanded refrigerant returned from the evaporator. Movement of the bellows 42, which has an end piece 42^a soldered or welded to a link rod 43, causes reciprocation of the linkrod 43 connected by rocking levers 44 to a master valve member 45. The master valve member 45 (Fig. 5) is provided with a plurality of notches 50 so that a spring pressed ball 51 engaging in the notches permits step-by-step movement of the master valve member. Each step causes one of a plurality of slots 52 to be connected to, or disconnected from, a source of oil pressure through an oil pressure tube 53. Each of the slots 52 is connected to a short tube 54 leading to a cylinder 55 in which is mounted a spring loaded unloader piston 56 connected to unloading mechanism including a yoke 57 adapted to ride on a ramp 58 and to be thereby moved axially as the piston 56 moves the yoke 57 longitudinally. The yoke causes axial movement of a ring 59 having unloader pins 60 mounted thereon, which when moved axially outward cause the suction valve 35 to be held open continuously whereby the cylinder is unloaded or prevented from compressing refrigerant. The position of the variably movable valve part 45, therefore, controls the number of unloader pistons 56 to which oil pressure is applied, and hence controls the number of cylinders in operation. When, as disclosed in Fig. 5, all but one of the slots 52 are connected to tube 53 through the annular space 61 surrounding the reduced portion of valve member 45, all but one of the individual cylinders will be loaded or operating. When valve member 45 is moved inwardly the length of another notch 50, two cylinders will be unloaded since another one of the unloader

cylinders 55 will be disconnected from the source of oil pressure. Oil pressure is applied to the unloading mechanism through the master valve from a pressure lubrication pump (not shown), details of which may be ascertained from the aforesaid Neeson Patent No. 2,185,473. As disclosed in the aforesaid patent, the oil pressure pump operates coextensively with operation of motor 21 so that no oil pressure will be supplied to the master valve 26 unless the motor is operating, and since it takes a short while for the pressure to be built up by the oil pump it is apparent that all cylinders will be unloaded during starting, thereby preventing large starting current inrush. It is also apparent that after oil pressure is available a number of cylinders will be unloaded depending upon the position of the linkrod 43.

The aforesaid Neeson Patent No. 2,185,473 discloses that the position of linkrod 43 may be controlled by the degree of compression of the flexible, metallic bellows 42, which compression is effected by the pressure of the gas in the space 41 connected to the suction side of the refrigerating system through the port 40. The pressure of the gas against bellows 42 operates against a compression spring 65 positioned between the end of the bellows and a disk 66. The disk has wings 66^a at opposite sides projecting through slots in a threaded sleeve 67. The sleeve is secured as by soldering or welding to an apertured member 68, to which the bellows 42 is secured. A nut 69 threaded on the sleeve 67 determines the position of the disk 66 and consequently, the compression of the spring 65. The link rod 43 has a reduced outer end on which is threaded a nut 69^a serving to guide the rod in the sleeve 67. A lock nut 69^b retains the nut 69^a in position. In the aforesaid patent, it is explained that the compression of the spring 65 controls the unloading pressure of the master valve so that the suction pressure of the refrigerating system may be controlled within reasonable limits. However, it has been found in some instances that the pressure of the gas returning to the compressor is not quite an adequate measure of the conditions in the system that require unloading. Accordingly, I have devised means for controlling the suction pressure at which unloading occurs and for controlling the position of the master valve part 45 directly in response to one or more conditions of the medium being cooled by the evaporator 23 such as temperature, humidity, or pressure.

As seen in Fig. 1, I provide an air pressure control system including an air compressor 70 operated by a motor 70^a and discharging into a pressure tank 71. The motor 70^a is controlled by a pressure-responsive device 70^b, which causes the motor to operate when the pressure in the tank 71 falls below a predetermined amount, the device 70^b being connected in electric power lines 70^c. Air is discharged from the tank 71 through a pipe 71^a in which is located a pressure-reducing valve 71^b, into a tank 71^c. A pipe 72 discharges compressed air from the tank 71^c through pipes 72^a and 72^b into two pressure regulating valves 73 and 73^a. Valve 73 includes a pair of fixed orifices 74 and 74^a which maintain a steady discharge of compressed air at a constant pressure depending upon the pressure maintained in tank 71 by the device 70^b and the motor 70^a. The tank 71 has a safety blowoff 75. The valve 73 has a space 76 into which orifice 74^a discharges. The space 76 of valve 73 is connected to pipes 77 and 77^a

which join in pipe 78, which branches into pipes 78^a and 78^b leading to housings 79 and 80, respectively, each participating in the control of one of the master valves 26. The pressure exerted in the housings 79 and 80 is controlled by regulating the pressure in pipe 77 which is accomplished by valve 73 and by a second valve 73^a interposed in parallel relation with valve 73 and connecting pipes 72 and 77. Valve 73^a includes a first chamber 76^a operatively connected to pipe 72^b and a second chamber 76^b operatively connected to pipe 77^a. A partition 76^c which separates chambers 76^a and 76^b is provided with an orifice. A plunger 81^a cooperates with this orifice to form a variable orifice valve means adapted to vary the amount of air admitted to chamber 76^b. The plunger 81^a is controlled by a diaphragm 82^a and return spring 83. The position of the diaphragm 82^a and plunger 81^a are controlled by pressure in suction line 85 leading from evaporator 23. This pressure is communicated by a line 85^a to the diaphragm 82^a. It is obvious that as the suction pressure in line 85 increases the diaphragm 82^a and plunger 81^a are forced downward in Fig. 1 thereby increasing the amount of air admitted to chamber 76^b and housings 79 and 80. The valve 73 includes a means for bleeding air to the atmosphere to load the compressor. This means comprises a plunger 81 operated by a bellows 82 and a return spring 83. The position of the plunger 81 is controlled by the pressure in a part 84 connected to the space of which bellows 82 comprises a movable wall. Part 84 contains a fluid reacting to a condition of the air or fluid medium surrounding it, such as temperature, humidity, pressure etc. As temperature rises, for example, bellows 82 is depressed and the pressure in space 76 drops as a result of increased opening of the valve controlled by plunger 81. The orifices 74 and 74^a provided in valve 73 are required to provide a restriction so that when valve 73^a is open a pressure can be built up in pipe 78 even if the valve 73 is open. When valve 73^a closes after the compressor has been unloaded the pressure in housings 79 and 80 is relieved through valve 73 when this latter valve is open.

As seen in Fig. 5, tube 78 is connected to a ring 86 forming part of the casing 80. The rest of the casing is composed of a fitting 87 threaded on the ring 86, a seal 88 between the fitting and the ring, and a dome member 89 with a generally hemi-spherical end joined to the fitting as by soldering or welding. The ring 86 has an inwardly extending flange 90 by which the casing 80 is attached to an end part 91 of the compressor with the aid of screws 92. The screws also attach the apertured member 68 to the end part 91. The pressure of the air or gas in tube 78 is transmitted through the casing 80 and acts against the inner side of the bellows 42 so as to tend to expand it. The change of pressure exerted by the air pump through the tube 78 by way of valve 73 acting in response to change in condition of the medium being cooled and by way of valve 73^a acting in response to high suction pressure in line 85 is preferably so selected as to add or subtract from the effect of spring 65 without rendering its effect negligible so that control of the master valve 45 through the bellows 42 is retained by the suction pressure of the compressor, the change in air pressure merely acting against the inner side of the bellows to modify the control of the master valve.

The operation of the present invention is as

follows: The compressor forces hot refrigerant gas into the condenser where the refrigerant is liquefied at the condensing pressure. The refrigerant is expanded in the evaporator 23 and extracts heat from the air or other surrounding medium. The expanded refrigerant is returned to the compressor and through the suction manifold 34 into the cylinders where it is again compressed. The suction pressure, which reflects the load on the evaporator, exerts pressure on the bellows 42 which tends variably to control the position of the unloader valve part 45. However, this control of the unloader valve part 45 is modified by the part 84 responsive to a condition such as temperature, pressure, humidity, etc., in the duct 24 and by a high suction pressure on the line 85, since the air or gas pressures in the housings 79 and 80 and the inner side of bellows 42 are determined by the part 84 and the return line 85. As the air pressure varies, there is inward or outward movement of the valve part 45 in steps controlled by the ball 51 riding in the notches 50. The movement of the master valve part 45 controls the connecting or disconnecting of one or more of the unloader cylinder spaces 55 and the source of fluid pressure through tubes 53 and 54. When pressure is applied to a cylinder space 55 the piston 56 therein is moved inward and causes the yoke 57 to ride down on ramp 58, thus dropping the pins 60 from the suction valve 35 and allowing the cylinder to compress gas. Disconnection of the cylinder space 55 from the source of fluid pressure causes the cylinder to become unloaded. In this manner the number of cylinders in operation varies so that the capacity of the compressor varies directly in response to the temperature produced by the evaporator.

The valve 73^a acts to modify the control of the master valve 45 only when the suction pressure in the return line 85 is very high. A high suction pressure is due to a heavy load on the refrigerating system, which may, for example, occur when a food locker or building cooled by the system is first being cooled. The load required to bring the temperature down to the desired value is many times heavier than that required to maintain the desired value of temperature. It is economically desirable to select a refrigerator system for the low rating required for maintenance of a certain temperature instead of one of a high rating required for lowering to the certain temperature. Yet the system should not be overloaded. According to my invention, I prevent such overloading by making the compressor unloader responsive to a high suction pressure. This is accomplished by adjustment of the valve 73^a, which acts to adjust the pressure exerted on the inside of the bellows 42. When a certain high suction pressure is reached in the return line 85 such as would indicate overloading of the system, the plunger 81 changes the amount of opening of the variable orifice valve in the valve 73^a. This change in opening is reflected in an increased pressure in the chamber 76^b, which is communicated to the interior of the bellows 42.

Figs. 6 and 7 show a modified form of apparatus in which the modifying effect of a condition such as temperature, pressure, or humidity in the cooling duct 24 and a high suction pressure in the return line 85 is applied by electrical means to the valve rod 43. The reduced threaded end of the valve rod 43 is slidably guided in a sleeve 93 in which is threaded an adjustable bolt 94 providing a limit to the movement of the valve

rod 43 to the left. The sleeve 93 is suitably mounted in a cage 96, which is threaded upon the sleeve 67. The cage 96 may be adjusted by rotation along the sleeve 67 and a jam nut 97 prevents such rotation. A sleeve 98 is slidably mounted upon the sleeve 93 and within the threaded sleeve 67 and engages one end of a coil spring 99, the other end of which contacts the end piece 42^a of the bellows 42. The sleeve 98 is pivotally connected by screws 100 to and between the spaced ends of strips 101 forming a link 102. The other ends of the strips are appropriately joined to one another and are pivotally connected by means of a nut and bolt 103 to an arm 104 actuated by an electric motor 105, the arm having 15 its center of angular movement at 106. The motor 105 is bolted to a bracket 109 supported on the end part 91 of the compressor by screws 92.

As seen in Fig. 8, the motor 105 is controlled by windings 108 and 109, one being adapted to rotate the motor in one direction, and the other, in the opposite direction. Associated with the windings 108 and 109 are contact points 110 and 111, spaced as shown above and below a movable switch member 112 pivoted at 113. The switch member has legs 114 and 115, which extend respectively through coils 116 and 117. The coil 116 is connected in a line 118 at one end of which is connected a resistance 119 and at the other of which is connected a resistance 120. The coil 117 is connected in a line 121, at one end of which is connected the resistance 120 and at the other a movable arm 122 controlled by a pressure-responsive element 123. The arm 122 contacts a resistance 124 connected by a line 125 to the resistance 119. The resistance 119 is contacted by a movable arm 126 controlled by an element 127 responsive to a condition such as temperature, pressure, or humidity, the element being conventionally represented as a bellows. The arm 126 is connected in a line 128, connected to a secondary coil 129 of a transformer having a primary coil 130. High voltage is impressed across the primary coil 130, and a low voltage is taken from the secondary coil 129. A line 131 leads from a junction point 132 with the line 128 to the motor windings 108 and 109, which are shown to be connected in parallel with one another. The motor 105 controls an arm 133 connected by a link with an arm 135 contacting the coil 120 and connected by a line 136 with the secondary coil 129. The switch member 112 is connected to the line 136.

When, as viewed in Fig. 8, the portions of the resistances 119 and 120 to the left of the arms 126 and 135 equal the effective portion of resistance 124 and the portions of the resistances 119 and 120 to the right of the arms 126 and 135, the secondary current is divided equally between line 118 and lines 121 and 125. Thus the same pull is exerted by the coils 116 and 117 upon the legs 114 and 115 of the switch 112 and the left end of the switch is maintained as shown in Fig. 8, out of contact with the points 110 and 111. However, if more current flows through the coil 117 than through the coil 116, a greater pull will be exerted upon the leg 115 than upon the leg 114, and the left end of the switch moves up into contact with point 110, causing current to flow in the coil 108. This makes the motor 105 rotate in a clockwise direction as viewed in Fig. 8. If a greater current flows in the coil 116, the switch 112 contacts the point 111, causing current flow in the coil 109 and rotation of the motor 105 in a clockwise direction in Fig. 8. Rotation of

the motor causes angular movement of the arm 104 and movement of the sleeve 98 to the left or right. The sleeve 98 acts through the spring 99 against the plate 42^a of the bellows 42. This 5 adjusts the valve rod 43 and changes the suction pressure at which the compressor unloads.

Any change from the position of equilibrium of Fig. 8 in which the switch 112 causes no current to flow either in the coil 108 or in the coil 109 is 10 brought about by a change in position of the arm 126 or the arm 122 due to a change in the condition to which the element 127 or 123 is responsive. Let it be assumed that the element 127 corresponds to the part 84 and valve 73 of Fig. 1, or in other words, that the element 127 is responsive to a condition of the medium being cooled in the duct 24, such as temperature, humidity, or pressure. Assume that the condition in question is temperature and that the element 127 will expand with increase in temperature and contract with decrease in temperature. Assume further that there is an increase in temperature. The resultant expansion of the element 127 will shift the arm 126 in a counterclockwise direction, 15 causing less of the resistance 119 to be to the left of the arm 126 and more of the resistance to be to the right. This causes a greater current to flow in the coil 116 than in the coil 117 and the switch 112 moves down to the point 111 causing current to flow in the coil 109. This causes the motor 105 to rotate in a counterclockwise direction as viewed in Fig. 8. The arms 133 and 135 are shifted counterclockwise, and the portion of the resistance 120 to the right of arm 135 decreases, and the portion to the left increases. 20 Thus compensation is provided for the decrease in the portion of resistance 119 to the left of arm 126 due to counterclockwise shifting of arm 126, and when the portions of the resistances 119 and 120 to the left of the arms 126 and 135 again 25 equals the effective portion of resistance 124 and the portions of resistances 119 and 120 to the right of arms 126 and 135, the current becomes the same in both coils 116 and 117, causing the switch 112 to move out of contact with point 111 30 to the position of Fig. 8. Current no longer flows in the coil 109 and rotation of the motor 105 and shifting of the arms 133 and 135 stop.

The above described counterclockwise rotation of the motor 105 as viewed in Fig. 8, due for example to an increase in temperature in the duct 24 causes the arm 104 to shift clockwise as viewed in Fig. 6. This shifts the sleeve 98 to the left reducing the force applied through the spring 99 to the plate 42^a. The bellows 42 is thus permitted to collapse somewhat, moving the valve rod 43 to the left and causing an increase in the amount of loading of the compressor.

From the above it can readily be pictured what a reduction in the temperature of the medium being cooled in the duct 24 will do to the apparatus of Figs. 6 and 7.

Consider that the element 123 corresponds in function to the valve 73^a and is subject to a suction pressure in the return line 85 so as to act in response to a high suction pressure indicative of overloading of the system. Assume that the element 123 is so connected with the return line 85 that this undesirable high suction pressure will collapse the element 123 to the point where the arm 122 reduces the effective portion of the resistance 124. This increases the current in coil 117, causing switch 112 to move up into contact with point 110. Current now flows in coil 108, 50 causing clockwise rotation of motor 105 as viewed

in Fig. 8. This causes clockwise shifting of arms 133 and 135 and an increase in the portion of the resistance to the right of arm 135. When the arm 135 has shifted sufficiently in a clockwise direction, the various resistances are so balanced as to cause the same flow of current in coils 116 and 117, and the switch 112 returns to the neutral position of Fig. 8, and the motor 105 is stopped. In the meantime, the arm 104 has shifted in a counterclockwise direction, moving the sleeve 98 to the right and causing it to act through the spring 99 to urge the plate 42^a of the bellows 42 to the right. This moves the valve rod 43 to the right and thereby increases the amount of the unloading of the compressor.

The apparatus of Figs. 6 and 7 provides for modification of the control of unloading of a compressor determined by suction pressure through electrical means that are responsive to two different conditions occurring simultaneously, for example, a condition of a medium being cooled such as temperature, pressure, or humidity and another condition such as high suction pressure in the return line of the compressor.

The apparatus of Fig. 9 is also electrically controlled in the manner illustrated in Fig. 8, but differs from that of Figs. 6 and 7 in certain respects. A disk 137 engages the left end of the valve rod 43. One end of a coil spring 138 engages the disk 137, and the other end is engaged by a sleeve 139. The sleeve and spring are mounted within the threaded sleeve 67. The sleeve is pivotally connected to and between the spaced ends of strips 101 forming the link 102, which is pivotally connected by nut and bolt 103 to the arm 104, actuated by the electric motor 105. The motor may be controlled by a means like that of Fig. 8. The motor may act through rotation in a certain direction to produce a counterclockwise shifting of arm 104, which brings about movement to the right of sleeve 139. The sleeve urges the spring 138 against the disk 137, causing the valve rod 43 and bellows disk 42^a to be urged to the right. This action increases the unloading of the compressor.

Rotation of the motor 105 in the opposite direction causes clockwise shifting of arm 104 and movement to the left by link 101 and the sleeve 139. The compression of the spring 138 is decreased, and the valve rod 43 moves to the left under the action of the bellows 42. The unloading of the compressor is thus decreased. The compression spring 65 acting between the bellows disk 42^a and the disk 66 positioned by the nut 69 threaded on the sleeve 67 resists collapse of the bellows 42 by the compressor suction pressure.

I claim:

1. Unloading mechanism for a variable capacity compressor adapted to be connected to a cooling system and having a plurality of compressing cylinders, each of a number of which may be selectively rendered inoperative in order to vary the capacity of the compressor, comprising a plurality of individual cylinder unloading means each operatively associated with a single cylinder, fluid pressure creating means for operating said individual cylinder unloading means, means for selectively connecting said fluid pressure creating means to said individual cylinder unloading means comprising a master valve including a valve rod adapted to be selectively positioned at a plurality of positions, and means for selecting the position of said valve rod comprising a spring biased to move said valve rod in a first direction, a bellows subjected on one side to the suction

pressure of said compressor and operating against said spring for returning said valve rod in the opposite direction to a plurality of successive positions when the suction pressure rises successively above a number of predetermined pressures, means for supplying pressure fluid against the other side of the collapsible bellows as to tend to expand the same for moving said valve rod in said first direction against the force exerted

10 on the bellows by the aforesaid suction pressure, and means for controlling the extent of movement of said valve rod caused by the action of pressure fluid against the said other side of the bellows, said controlling means comprising a de-

15 vice for regulating the pressure exerted by the pressure fluid and means responsive to the temperature of the medium subjected to the action of the cooling system and responsive to the suction pressure of the compressor for variably controlling the setting of the device.

2. Unloading mechanism for a variable capacity compressor adapted to be connected to a cooling system and having a plurality of compressing cylinders, each of a number of which may be

25 selectively rendered inoperative in order to vary the capacity of the compressor, comprising a plurality of individual cylinder unloading means each operatively associated with a single cylinder, fluid pressure creating means for operating

30 said individual cylinder unloading means, means for selectively connecting said fluid pressure creating means to said individual cylinder unloading means comprising a master valve including a valve rod adapted to move in a first direction

35 to effect the fluid connection and cylinder loading and to move in a second direction to interrupt the fluid connections and unload the compressor cylinders and to be selectively positioned at a plurality of positions each of which

40 correspond to the loading of a selected number of said cylinders, and means for selecting the position of said valve rod comprising a bellows operatively connected to said valve rod, means for supplying pressure fluid against one side of the

45 bellows so as to tend to move said valve rod in said second direction to unload compressor cylinders, and means for controlling the extent of movement of said valve rod caused by the action of the pressure fluid on said bellows comprising

50 a device for regulating the pressure exerted by the pressure fluid and means responsive to high compressor suction pressure and low temperature of the medium subjected to the action of the cooling system for providing increased fluid pressures to move said valve rod in said second direction to effect unloading of said compressor cylinders.

3. A cooling system comprising a compressor-condenser-evaporator system of refrigeration,

60 the compressor of which comprises a plurality of cylinders and means to vary the number of cylinders compressing refrigerant comprising individual cylinder unloading means associated with each of a number of said cylinders, fluid

65 pressure means for operating said individual cylinder unloading means including a master valve having a valve rod capable of being moved to a number of control positions to vary the number of said individual cylinder unloading means oper-

70 atively connected to said fluid pressure means, and means for selecting the control position of the rod, said means comprising an expansible-collapsible device subjected at one side to the suction pressure of the compressor, means for sub-
75 jecting the other side of the expansible-collapsible

device to pressure fluid, and control means operative to regulate the pressure of said last mentioned fluid in response to variations in both compressor suction pressure and evaporator temperature.

4. In a refrigerating system of the compressor-condenser - evaporator type, capacity - varying means associated with the compressor for altering the amount of refrigerant compressed, said capacity-varying means including a master valve capable of being moved to a number of control positions, an expansible-collapsible device connected with the master valve and subjected over a first pressure area to the suction pressure of the compressor to move the master valve, means for supplying pressure fluid to oppose said suction pressure on a second and substantially equal pressure area associated with said master valve, and means responsive to the temperature of the medium being cooled by the evaporator of the system and to compressor suction pressure for varying the pressure of the pressure fluid.

5. In a refrigerating system of the compressor-condenser-evaporator type, capacity-varying means associated with the compressor for altering the amount of refrigerant compressed, means responsive to increased suction pressure of the compressor for exerting control over the capacity-varying means tending to increase the compressor capacity, means responsive to a high temperature of the medium being cooled by the system for adjusting the control in a direction tending to increase the compressor capacity and means responsive to compressor suction pressures above a predetermined value tending to decrease the compressor capacity.

6. In a refrigerating system of the compressor-condenser-evaporator type, capacity-varying means associated with the compressor for altering the amount of refrigerant compressed, means responsive to suction pressure of the compressor for exerting control over the capacity-varying means, means responsive to the temperature of the medium being cooled by the system for adjusting the control exerted by the means responsive to suction pressure, and means responsive to a high suction pressure indicating overloading of the compressor for modifying the control exerted by the capacity-varying means in such a way as to reduce the amount of refrigerant compressed.

7. In a refrigerating system of the compressor-condenser-evaporator type, capacity-varying means associated with the compressor for altering the amount of refrigerant compressed, a pressure-movable device associated with the capacity-varying means so as to cause the same to decrease the amount of refrigerant compressed when subjected to pressure from one direction, means responsive to a low temperature of the medium being cooled by the system for applying pressure in the said one direction over a predetermined area to the pressure-movable device and means responsive to an overloaded compressor condition for applying pressure in the said one direction over an equal area to the pressure-movable device.

8. In a refrigerating system of the compressor-condenser-evaporator type, capacity-varying means associated with the compressor for altering the amount of refrigerant compressed, an expansible-collapsible device subjected on its outer side to suction pressure of the compressor and associated with the capacity-varying means so as to cause control thereover to be exerted by suction pressure, a first spring engaging the inner side of the expansible-collapsible device, means

engaging the first spring for causing it to exert a predetermined force against the expansible-collapsible device, a second spring acting against the expansible-collapsible device, and means responsive to the temperature of the medium being cooled by the system and a high suction pressure indicative of overloading of the compressor engaging the second spring for causing it to exert a variable force against the expansible-collapsible device in opposition to the force exerted on the device by the suction pressure for modifying the control exerted by the suction pressure.

9. In a refrigerating system of the compressor-condenser-evaporator type, capacity-varying means associated with the compressor for altering the amount of refrigerant compressed, an expansible-collapsible device subjected on its outer side to suction pressure of the compressor, a rod extending through and fixed to an end of the expansible-collapsible device, means associating the end of the rod outward of the expansible-collapsible device with the capacity-varying means for causing the suction pressure to act through the device and the rod for exerting control over the capacity-varying means, a first spring engaging the inner side of the said end of the device, means engaging the first spring for causing it to exert a predetermined force against the device in opposition to the force exerted thereon by the suction pressure, a second spring acting against the other end of the rod, and means responsive to the temperature of the medium being cooled by the system and a high suction pressure indicative of overloading of the compressor for acting against the second spring to cause it to act with a variable force through the rod against the device in opposition to the force of the suction pressure acting thereagainst for modifying the control exerted on the capacity-varying means by the suction pressure.

10. In a refrigerating system of the compressor-condenser-evaporator type, capacity-varying means associated with the compressor for altering the amount of refrigerant compressed, means responsive to suction pressure for exerting a control over the capacity-varying means, an electric motor for modifying the control exerted by the means responsive to suction pressure over the capacity-varying means, parallel lines connected with a power source and having resistance, means responsive to disturbance of a predetermined relation of the resistances in the parallel lines for operating the motor, means responsive to the temperature of the medium being cooled by the system for varying the relation of the resistances in the parallel lines, means responsive to high suction pressures indicative of overloading of the compressor for varying the relation of the resistances in the parallel lines, and means driven by the motor for restoring the predetermined relation of the resistances in the parallel lines to stop the motor.
